(57) **CLAIM**

The ornamental design for an actuator jaw, as shown and described.

DESCRIPTION

The nature of this product is as a clamping jaw used in connection with a toilet brush to hold a brush head.

FIG. 1 is a right, top, front perspective view of an actuator jaw embodying our new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a front elevational view thereof; and,

FIG. 7 is a cross sectional view and partial rear elevational view thereof taken along line 7—7 of FIG. 2.

The broken line representations of an actuator rod and actuator projection in FIGS. 1—6 are for purposes of illustration only, and form no part of the claimed design.
